UNITED STATES PATENT OFFICE.

ALBERT J. LINDEMANN, OF MILWAUKEE, WISCONSIN.

VAPOR-STOVE.

SPECIFICATION forming part of Letters Patent No. 390,870, dated October 9, 1888.

Application filed May 1, 1886. Serial No. 200,765. (No model.)

To all whom it may concern:

Be it known that I, ALBERT J. LINDEMANN, of Milwaukee, in the county of Milwaukee, and in the State of Wisconsin, have invented certain new and useful Improvements in Vapor-Stoves; and I do hereby declare that the following is a full, clear, and exact description thereof.

My invention relates to vapor-burning stoves; and it consists in providing the burner-caps with deflecting flanges or cornices, whereby I spread the flame over a greater area, and thus cause a better diffusion of heat than is ordinarily the case in stoves of this character; and in stoves employing two or more burners my invention further consists in connecting the flange or cornice of each of these burners with one, two, or more conducting-tubes that terminate in proximity to that of another burner or burners in the series, whereby in case one of said burners may be lighted and the other or others turned on an automatic ignition of the latter will be accomplished, this automatic ignition also taking place in case of the accidental going out of the flame or leakage from any cause whatever of one or more of the burners in the series less than the whole number, thus causing a consumption of the escaping vapors and preventing unpleasant odors and dangerous gases from accumulating in the apartment where the stove may be employed.

In the accompanying drawings, Figure 1 represents a plan view of a vapor-stove illustrating my invention, and Fig. 2 a detail sectional view of the same.

Referring by letter to the drawings, A represents the top of a single generator vapor-stove; B, the mixing-chamber; C, the induction-tubes, and D the burner-needles. These parts being all of the usual well-known construction and arrangement, it is not deemed necessary to describe them in detail.

Each cap E of the several burners F is provided with a flange or cornice, a, that is preferably concave upon its under side, whereby a gutter, b, is formed that entirely surrounds the main portion of the burner, to which this cap may be applied, and serves as an accumulator for the generated vapors that escape from said burner prior to ignition. The flange or cornice not only serves the purpose just de-

scribed, but also acts to spread the flame, and thereby cause its diffusion over a greater area; thus giving each burner a greater heating capacity without increasing the consumption of the vapor-producing substance. 55

The flange or cornice a of each burner is connected to one, two, or more conducting-tubes, G, each of the latter terminating in proximity to another of the burners in the series. In case one burner is lighted and the fluid turned on for another, the generated vapor for the latter will naturally accumulate under the flange or cornice a of its respective burner-cap, and will be deflected thereby into and seek an outlet at that end of a conducting-tube, G, that terminates in proximity to said lighted burner, the travel of this vapor being accelerated by the suction of the flame. 60

The moment any of the vapor comes in contact with the flame ignition takes place and instantaneously extends back through the conducting-tube to the burner from which said vapor may be escaping, thereby lighting the 65 same for work. 70

Should either of the burners be blown out or otherwise accidentally extinguished, or leak from any cause whatever, the above described operation will take place, thereby causing 80 said burner to reignite and continue the consumption of the vapor, thus preventing the latter from escaping out into the apartment where the stove may be set up.

The parts of the burners exclusive of the 85 caps are of the usual construction, and the latter are severally retained in operative position by the ordinary means, and though I have described my improvements in connection with a vapor-stove having a single generator, they 90 are equally applicable to stoves employing individual generators for each burner, or, in fact, any style of burner.

In stoves that generate the vapor from a single burner, or that have more than two burners, it is preferred to have the conducting-tubes G, that connect with the flanges a of the other burners, terminate in proximity to the generating central or main one, for the reason that the latter is the one usually first lighted 95 and most likely to remain so. 100

The generating or fundamental burner may have either one or more conducting-tubes connected to its flange to correspondingly lead to

either one, two, or more of the other burners in the series. The greater the number of these conducting-tubes and their several terminals with relation to said other burners the quicker 5 the automatic reignition of this generating or central burner will be effected in case of its being accidentally extinguished, as the escaping vapor will be attracted to the burner or burners that may remain lighted.

10 Having thus fully described my invention, what I claim as new, and desire to secure by Letters Patent, is—

15 1. In a vapor-stove, the combination of two or more burners, one of which has its cap provided with a deflecting-flange, and one or more tubes connected to said flange, and each tube arranged to terminate in proximity to another of the burners in the series, substantially as set forth.

20 2. In a vapor stove, the combination of two or more burners, each of which has the cap thereof provided with a deflecting-flange, and one or more tubes connected to each flange, and each tube arranged to terminate in proximity 25 to another of the burners in the series, substantially as set forth.

3. In a vapor-stove, the combination of two or more burners, each of which has the cap thereof integrally formed with a deflecting-flange that is concave upon its under side, and 30 one or more tubes connected to each flange, and each tube arranged to terminate in proximity to another of the burners in the series, substantially as set forth.

4. In a vapor-stove, the combination of a 35 single generating-burner having its cap provided with a deflecting-flange, one or more non-generating burners that also have their caps individually provided with a deflecting-flange, and one or more tubes connected to 40 the flange of each non-generating burner, and each tube arranged to terminate in proximity to the generating-burner, substantially as set forth.

In testimony that I claim the foregoing I have 45 hereunto set my hand, at Milwaukee, in the county of Milwaukee and State of Wisconsin, in the presence of two witnesses.

ALBERT J. LINDEMANN.
